UNITED STATES PATENT OFFICE.

ALFRED L. BOEGEHOOLD, OF DAYTON, OHIO, ASSIGNOR TO GENERAL MOTORS RESEARCH CORPORATION, OF DAYTON, OHIO, A CORPORATION OF DELAWARE.

INTERNAL-COMBUSTION-ENGINE CYLINDER AND PROCESS OF MAKING SAME.

Original application filed December 14, 1922, Serial No. 606,797. Divided and this application filed December 19, 1924. Serial No. 757,070.

The present invention relates to heat exchange vessels, and processes of making them. In the preferred form of embodiment which has been chosen for the purpose of description and illustration, the invention relates particularly to air cooled internal combustion engines cylinders and to processes of securing in permanently effective heat conducting relation to the cylinder, cooling fins of a highly heat conducting metal.

This is a division of my co-pending application, Serial #606797, filed December 14, 1922.

15 Among the objects of the invention is to increase the economy and efficiency of processes of making such articles and at the same time form an article which is itself more efficient in its functions.

20 Another object is the decrease in the number of operations in such processes, thereby shortening the time usually considered necessary and cutting down the cost.

25 Further objects and advantages of the present invention will be apparent from the following description, reference being had to the accompanying drawings, wherein a preferred form of embodiment of the present invention is clearly shown.

30 In the drawings:

Fig. 1 illustrates partly in vertical section a cylinder produced by the present process.

Fig. 2 is a vertical section through a mold prepared for the casting operation and having a cylinder barrel and prepared fins set therein.

Fig. 3 is a horizontal section of Fig. 2, on line 3—3.

Fig. 4 is an enlargement of a portion of Fig. 3.

Fig. 5 is a view similar to Fig. 4 but illustrating a modification of the finning method.

45 The prepared material used in making the present type of cylinder are those mentioned in the specific description immediately following but it should be understood that other materials may be used provided they are suitable for the process and have properties adapting them for the functions which they will have in the finished cylinder.

50 The cylinder shown in Fig. 1 preferably consists of a steel barrel 10 having a cast on iron base 11. It also shows a bi-metallic head consisting of a cast in plate of iron 12

and a cast on plate or equalizer 13 of copper, these being the preferred metals used for such parts or portions.

Surrounding the upper portion of barrel 10 is a set of cooling fins 14 which will be 60 more particularly described later. And between these fins 14 and barrel 10 is a thin layer of copper 15.

The bonds between the several portions, when the process is properly carried out are 65 permanent metallic bonds and are efficiently heat conductive, which property is highly desirable at the junction between the fin material and the cylinder barrel and head and between the head materials and between 70 these latter and the barrel.

In carrying out the process, a steel tube is set in a suitable mold and an iron plate of suitable thickness cast in one end thereof in any well known manner so as to produce 75 a welded junction between the two metals. Such a prepared tube is indicated at 10 and 12 in Fig. 2.

A suitable mold is then prepared, as indicated in Figs. 2 and 3, having embedded in 80 its walls a set of cooling fins 14 with their bases projecting into or forming a wall of the mold proper. The mold proper should be of sufficient size to allow the tube 10 to be positioned therein with a small annular 85 space between the tube and the walls of the mold as indicated at 20 in Figs. 2 and 4. The tin plated tube 10 is then properly positioned in the mold with a space 21 beneath it for the molding of the head portion 13.

Around the upper end of the tube there is also formed a second mold 30 for casting base 11.

There are provided also a gate 35 and riser 90 36 for the lower mold and a gate 37 and riser 38 for the upper mold.

When the molds have been thus prepared with the fins 14 and tube 10 in place, a thin cup of baked core material 40 is placed inside of tube 10 and after runner boxes have been placed therein as indicated, the mold is ready for pouring.

The pouring operation is conducted as follows; first molten iron is poured into 105 cup 40 for the purpose of highly heating tube 10 and head portion 12. Then after an interval of a few seconds, to give the tube a chance to get hot, iron for the base 11 is poured in through gate 37 and, immediately 110

thereafter, copper is poured through the gate 35.

The tube being thoroughly and highly heated, the copper runs in readily and fills space 21 and rises in annular space 20 welding itself to plate 12, fins 14 and tube 10 forming a permanent and effective heat conductive bond.

The cylinder is then removed from the mold cleaned and finished.

A modification of the process just described consists in casting thin cooling fins of the copper at the same time that head is cast, instead of setting previously formed fins in the mold as indicated. In this modification the mold is prepared and the tube 10 positioned therein in the same manner as has been described except that thin forms are prepared therein in which the cooling fins are cast. A section of a portion of such a mold is shown in Fig. 7 in which 10 is the steel tube, 20 the annular space and 50 the forms for the cast cooling fins.

While the forms of embodiment of the invention as herein shown and described constitute preferred forms, it is to be understood that other forms might be adopted. All

coming within the scope of the claims which follow.

What I claim is follows:

1. The process of producing internal combustion engine cylinders which comprises setting a series of fins in a mold with their inner ends or bases exposed to the interior of the mold; positioning a cylinder, provided with a thin head, within the mold in such fashion as to leave an annular space between it and the fin bases and so as to have a space for additional head metal; lining the cylinder with a protecting layer; pouring into the cylinder molten metal for preheating same; and casting in the annular space and head space another metal to join the cylinder and fins and thicken the head.

2. In a process of casting copper cooling elements upon ferrous metal cylinders, preheating the cylinder by filling it with molten cast iron, the cylinder being prevented from sticking to the iron by a thin protective layer.

In testimony whereof I hereto affix my signature.

ALFRED L. BOEGEHOOLD.
